UNITED STATES PATENT OFFICE.

HARRY A. LEONARD, OF HOPEDALE, MASSACHUSETTS, ASSIGNOR TO DRAPER CORPORATION, OF HOPEDALE, MASSACHUSETTS, A CORPORATION OF MAINE.

SPINNING OR WINDING MACHINE.

1,304,893.

Specification of Letters Patent. Patented May 27, 1919.

Application filed March 12, 1918. Serial No. 222,020.

To all whom it may concern:

Be it known that I, HARRY A. LEONARD, a citizen of the United States, residing in Hopedale, in the county of Worcester and State of Massachusetts, have invented an Improvement in Spinning or Winding Machines, of which the following description, in connection with the accompanying drawings, is a specification, like characters on the drawings representing like parts.

The invention to be hereinafter described relates to spinning or winding machines for winding yarn on carriers or bobbins, and more particularly to the builder mechanisms of such machines.

In looms of the automatic type wherein a feeler is employed to feel for the yarn in the shuttle and initiate replenishment of filling prior to complete exhaustion thereof, it is desirable that sufficient filling be left on the bobbin or carrier after an indication for replenishment to avoid partial picks or curling of the yarn in the shed on the final pick preceding replenishment. This has been accomplished in some cases by placing one or more layers of filling on the carriers or bobbins to constitute a suitable supply for the purposes stated before the regular or service windings are commenced. Such suitable supply has been furnished by preliminary windings of different traverse from the regular or service windings, or by the formation of a distinctive bunch. Where the carriers or bobbins have been slotted or recessed for the reception of the feeler at the critical period, it has been proposed to place the preliminary windings or bunch at or beyond one end of the slot, so that when the feeler calls a change such bunch or windings have constituted the reserve supply.

The present invention provides simple and effective means for producing such preliminary windings or bunches, and while especially adapted for placing a reserve supply of yarn upon slotted carriers or bobbins, it may also be employed with advantage in connection with other forms of carriers or bobbins. An important feature of the invention consists of two cams, one a primary winding cam and the other a service winding cam, rotatably fixed to their operating shaft in relatively set rotative positions for action upon the builder arm, and means for selectively determining which of said cams

shall be operatively effective. Another feature of importance is the locking means and the manner of its operation to maintain the primary winding cam in operative relation to the builder arm until the preliminary windings are completed and then to release the said cam and permit the service winding cam to control the traverse.

These and other important features of the present invention will best be made clear from the following description and accompanying drawings showing one good, practical embodiment thereof.

In the drawings:

Fig. 1 is a front elevation of a sufficient portion of a machine embodying the invention to make clear its construction and mode of operation;

Fig. 2 is an enlarged section on the line 2—2 of Fig. 1;

Fig. 3 is a detached detail showing the action of the holding latch as it frees the manually-operated controlling means;

Fig. 4 is an enlarged detail showing parts of the manually-operated controlling means, some portions being broken away;

Fig. 5 is a perspective detail showing the latch and its operative relation to the manually operated controlling means;

Fig. 6 is an enlarged section on the line 6—6, Fig. 2; and

Fig. 7 is a similar section on the line 7—7, Fig. 2.

The invention is herein illustrated as applied to a spinning machine of the ring type, wherein the main frame 1 is provided with the cross-piece or ladder 2, the top rail of which supports a series of spindles provided with whirls or pulleys 3 for rotating a series of yarn carriers or bobbins 4 mounted on the spindles. A lifter rail 5 has a series of rings 6 provided with usual travelers, and is supported by the lifter rod 7, the lower end 8 of which rests upon a stud or roll 9 adjustably mounted on the lever 10 pivoted at 11 upon a suitable bracket 12 extending from the lower rail of the ladder 2, and provided with a weight 13 for effecting upward traverse or movement to the ring rail. Extending upward from the lever 10 is a segment arm 14 to which is connected one end of a chain 15 by suitable means, such as the adjusting screw 16, the other end of the chain being secured to the winding drum 17.

carried by the builder arm 18 which is itself pivoted at 19, Fig. 2, to a suitable support. While only a single lever 10 and lifter rod 7 are illustrated, it is to be understood that 5 any suitable number of these may be employed and the levers may be connected, as usual, to move in unison and cause the ring rail 5 to move up and down under control of the builder motion, as is common and well 10 understood in this general class of machines.

The drum 17, Fig. 2, is mounted on the builder arm 18 and is connected for rotative movement with a worm wheel 20 actuated by a worm 21 carried by the builder arm. The 15 worm 21 has connected thereto the pick wheel 22, the teeth of which are adapted to be engaged by the pawl 23 carried by an arm 24 which is actuated by the rod 25, as the builder arm is raised and lowered. These 20 parts and their operation may be all as usual, and as they are well understood by those skilled in the art, further explanation is unnecessary.

Mounted for rotative movement in the 25 main frame 1 is the cam shaft 26 which may be actuated from any suitable source of power, as by the gear wheel 27, Fig. 1. Connected for rotative movement with the cam shaft 26 are the primary winding cam 30 and the service winding cam. In the present 30 instance of the invention, the main frame 1, Figs. 6 and 7, has connected thereto the bearing 28, through which the cam shaft 26 extends and secured to the end portion 29 of the cam shaft 26 is the service winding cam 30. The service winding cam 30 may be secured to the shaft 26 in any appropriate manner, but as herein shown, the cam is provided with a hub portion 31 which extends 35 over an exterior bearing portion 32 of the bearing 28, and the service winding cam is held to the the cam shaft 26 by a suitable end securing means 33. The hub portion 31 of the service winding cam has mounted thereon 40 the primary winding cam 34 which is secured to the service winding cam for rotative movement therewith, and in unison with the cam shaft 26. In the present instance, the primary winding cam 34 is 45 splined or keyed to the hub of the service winding cam 30 as at 35, Figs. 6 and 7, the construction being such that while the primary winding cam 34 and the service winding cam 30 rotate in unison, the primary 50 winding cam has sliding axial movement toward and from the service winding cam for a purpose that will presently appear.

Between the primary winding cam 34 and the service winding cam 30 is interposed a 55 yielding means normally acting to move the cams axially and relatively in a direction of separation. In the present instance the yielding means consists of a series of springs 36, each of which may be properly supported 60 in sockets 37 formed in or as part of the

service winding cam 30. Obviously, the number of springs 36 may be varied, but in the present instance, four of such springs are indicated as tending normally to move the primary winding cam 34 axially away from 70 the service winding cam 30.

The form and character of the primary winding and service winding cams may be varied to suit the particular conditions of use, but in the present instance the service 75 winding cam 30 has four cam portions about its periphery, each of which serves to cause an upward and downward movement of the ring-rail or yarn guides. The primary winding cam 34 as indicated in Figs. 2 and 80 3, is adapted to be moved into operative relation with the builder arm and after the prescribed number of traverses of primary windings have been made under its control to be automatically moved out of such operative relation with the builder arm to permit the service winding cam 30 to at once 85 take complete control. In the present instance of the invention, the primary winding cam has a traverse-controlling portion 90 to impart to the builder arm the desired number of traverses to produce the preliminary windings, and the service winding cam and primary winding cam are set with respect to each other in fixed rotative position 95 so that between the highest points 38 of the service winding cam the primary winding cam shall present its traverse controlling portions. This set condition or relation of the two cams is such that the primary winding cam comes into action at a point 39, for instance, after the ring-rail or yarn guides have been raised by the service winding cam acting upon the builder arm between the points 38, 39, as indicated 100 in Fig. 2. That is, when the primary windings are started, the first movement of the ring-rail or yarn guides is downwardly or toward the base of the bobbin or yarn carrier, and thereafter the ring-rail is given 105 110 the prescribed number of alternate traverses, dependent upon the character of the primary winding cam. Where the invention is applied to the winding of carriers or bobbins having slotted or recessed portions 115 into which the feeler extends at times, the set position of the cams is determined so as to place the primary windings at one end of the slot or recessed portion, preferably toward the head or base of the bobbin or 120 carrier. From an inspection of the cam construction as indicated in Figs. 2 and 3, it will be noted that as soon as the preliminary windings have been laid upon the carrier or bobbin, the full service traverse commences.

Mounted upon the builder arm 18 is a roll 40 which may be adjustably supported by a stud shaft 41 carried by the builder arm or a bracket secured thereto, whereby 125 130

the primary winding and the service winding cams may impart traverse movement to the builder arm.

As hereinbefore noted, the springs 36 normally tend to move the primary winding cam 34 away from the service winding cam 30 and such relation continues during service winding. When, however, it is desired to commence the winding operation on a fresh set of carriers or bobbins and to produce primary windings or a bunch, the primary winding cam 34 is moved toward the traverse cam 30 to bring its cam portion into operative relation with the builder arm and its roll 40. In the present instance of the invention this is effected by a manually-controlled lever 42, Fig. 1, having a hand portion 43 preferably located in convenient position for actuation by the attendant. The lever 42 is pivotally mounted at 44 upon a bracket 45 appropriately supported, and in the present instance shown as secured to the frame of the machine. The lever 42 has secured thereto or formed as integral therewith a toothed segment 46, the teeth 47 of which engage teeth 48 of a segment 49 secured to a rock shaft 50. The rock shaft 50 may be supported in any convenient manner, but as indicated in the present instance of the invention, the bearing 28 supports the rock shaft 50 below the shaft 26. Secured to the rock shaft 50 at each side of the cam shaft 26 are the fingers or dogs 51 which, when the primary winding cam 34 is moved to the left or into inoperative relation with the builder arm, stand at one side of the face of said primary winding cam. The position of the fingers or dogs 51 at such time is best indicated by dotted line, Fig. 7. From the construction described, it will be apparent that should the lever arm 42 be moved contra-clockwise into the position indicated in Fig. 1, it will, through the connections described, cause the fingers or dogs 51 to act upon the primary winding cam 34 and move it in opposition to the springs 36 to the right, or into operative relation with the builder arm 18 and its roll 40.

To hold the primary winding cam 34 in operative relation with the builder arm, a lock is provided. In the present instance of the invention, the lock comprises a member 52 adjustably secured to the builder arm by suitable means such as the bolt 53. The end portion of the lock member 52 is adapted to bear upon the face of the cam 34 when such cam is in operative position relative to the builder arm and thereby lock the cam from movement axially of the cam shaft by the springs 36. By mounting the lock 52 upon the builder arm, it may be conveniently lowered by foot depression of the builder arm to permit the primary winding cam 34 to be moved into operative relation with the builder arm or toward the service winding

cam 30. This movement of the primary winding cam may be effected in various ways, one convenient form of means for this purpose being the lever 42. When the primary winding cam has been moved into operative position it may be held there by the lock 52 which rises behind the cam 34 when the foot is removed from the builder arm. If desired, the builder arm may be conveniently lowered for engaging the lock 52 behind the cam by other means than the foot of the attendant. The primary winding cam has a series of openings or slots 54, any one of which, when in alignment with the lock, may permit the primary winding cam to move away from operative position. When bobbins or filling carriers are to be wound for use in broad looms, a greater quantity of reserve filling is required in the primary windings than where the carriers are to be used in narrower looms, and the present invention contemplates means for adapting the builder motion to either of these requirements. In the present instance of the invention, the primary winding cam has four slots 54 which permit movement of the cam away from operative relation with the builder arm at any one of four positions of the primary winding cam, the periphery of the cams being such between any two of said slots 54 to effect windings for use in looms of ordinary width. In preparing the filling carriers for such use, the attendant depresses the builder arm at the appropriate time, then shifts the primary winding cam into operative position or close to the service winding cam, whereupon the builder arm is permitted to rise, thereby placing the lock 52 back of the primary winding cam, substantially as indicated in Fig. 1. As the cams revolve the desired traverse will be imparted to the ring-rail, until, when an advancing slot 54 comes opposite the lock, the primary winding cam will be at once moved into inoperative position by the springs 36, and service winding will be resumed.

When, however, filling carriers are to be prepared for use in broad looms, and consequently a larger amount of reserve yarn is to be provided in the primary windings, it is desirable that a greater number of traverses be made by the primary winding cam before it is moved into inoperative position. To this end, the present invention provides means to continue the locked position of the primary winding cam as one or more of the slots 54 of the cam pass the lock 52. In the present instance of the invention in this respect, a latch is provided for holding the primary cam in operative position, as a slot 54 passes the lock.

The latch may be variously contrived, but as shown in the present instance of the invention comprises an arm 55 having a shoudered head portion 56 and pivotally mount-

ed at 57 to the bracket 45. A weight 155 connected to the arm 55, or a spring 58, one end of which is secured to the arm 55, and the other to the bracket 45 as indicated in Fig. 4, may serve to normally throw the latch to the left, Fig. 5, into locking position above the toothed segment 46, the construction being such that when the lever arm 42 has been thrown into the position indicated in Fig. 1, the fingers or dogs 51 will move the primary winding cam 34 into the position indicated in Fig. 6, whereupon the latch 55 will engage above the toothed segment arm 46 and maintain the dogs 51 pressing upon and holding the primary cam 34 in operative position to which it has been moved by the dogs. It is evident that so long as the dogs thus hold the primary cam, the latter cannot move to inoperative position away from the service cam even though one of the slots 54 comes opposite the lock 52. Ordinarily, sufficient reserve yarn will be provided in the preliminary windings for broad loom use by holding the primary winding cam in operative position for a half revolution, or while one of the slots 54 passes the lock 52 on the builder arm. In that case it is desirable that the latch be tripped to release the primary winding cam to movement after one of the slots 54 of the cam has traveled past the lock 52. To this end the latch 55 has a tripping device, which in the present instance of the invention, is mounted at 59 on the latch and has a shouldered portion 60 and a trip finger 61. Pins 62 attached to the service cam 30 are adapted to engage and move the finger 61. These pins may be made removable, so that when laying primary windings for broad looms a pin 62 may be placed in alternate holes 162 of the cam, thereby permitting the latch to hold the dogs and perforce, the primary winding cam in operating position while one of the slots 54 passes the lock 52 and then, tripping the latch, so that upon a half rotation of the primary winding cam, the latter may automatically move to inoperative position. If all four of the pins 62 are secured to the cam 30, then the attendant may depress the builder arm to permit the primary winding cam to move into operating position and hold the parts in such position until after the first pin adjacent the trip has passed the trip finger 61. This is preferred in some instances, as it does away with the attendant putting in and taking out the pins.

In order that the lever 42 may be moved to throw the fingers or dogs 51 into inoperative position when the latch 55 is tripped as described, a spring 63, Fig. 1, may be provided, one end of the spring being secured to the lever 42 and the other to a fixed part of the machine, or a weight 163, Fig. 5, may be employed.

66 The chain or other suitable connection

15 between the builder arm and segment 14 passes over a guide which, in the present form of the invention, comprises a pulley 64, Figs. 1 and 2, which is preferably supported in a cradle 65 sustained by suitable brackets 66, appropriately mounted on the machine frame as indicated in Figs. 1 and 2. The cradle 65 has a bearing portion 67 which conforms to the contour of the supporting element 68 of the pulley so that during the changing directions of the chain or connection 15 due to the action of the builder motion, the pulley or guide 64 may appropriately rock in its cradle.

What is claimed is:

1. In a machine of the character described, the combination of a series of spindles for supporting and rotating yarn carriers, yarn guiding means, a builder arm, primary and service winding cams for operating the builder arm, yielding means between the cams for shifting the primary winding cam out of operative relation with the builder arm, a locking member adapted to engage and hold the primary winding cam in opposition to said yielding means until the primary windings have been wound and then permit the primary winding cam to pass.

2. In a machine of the character described, the combination of a series of spindles for supporting and rotating yarn carriers, yarn guiding means, a builder arm, primary and service winding cams for operating the builder arm, a locking member mounted on the builder arm to engage and hold the primary winding cam in operative relation to the builder arm, and means for moving the primary winding cam out of engagement with the locking member when a predetermined position of rotation has been reached.

3. In a machine of the character described, the combination of a series of spindles for supporting and rotating yarn carriers, yarn guiding means, a builder arm, primary and service winding cams for selectively actuating the builder arm, yielding means for moving the primary winding cam in one direction relative to the service winding cam, and a locking member adapted to extend over the periphery of the primary winding cam to hold it during a predetermined number of traverses of the yarn longitudinally of the yarn carriers, said primary winding cam having an opening to permit passage of the locking member after the predetermined number of windings have been laid on the carriers.

4. In a builder motion, the combination of a builder arm, a shaft, a primary winding cam and a service winding cam mounted on the shaft, springs interposed between the cams for separating them longitudinally of the shaft, means for moving the

cams into close relation in opposition to said springs, and a lock for holding the cams in close relation.

5. In a builder motion, the combination 5 of a builder arm, a shaft, a primary winding cam and a service winding cam mounted on said shaft for selectively operating the builder arm, yielding means between the cams tending to move the primary winding 10 cam away from the service winding cam into inoperative relation with the builder arm, manually operated means for moving the primary winding cam into operative relation with the builder arm in opposition to 15 said yielding means, and a locking member acting to prevent movement of the primary winding cam by either of said means except at predetermined positions.

6. In a builder motion, the combination 20 of a builder arm, a shaft, a primary winding cam and a service winding cam mounted on said shaft for selectively operating the builder arm, yielding means between the cams tending to move the primary winding 25 cam away from the service winding cam into inoperative relation with the builder arm, manually operated means for moving the primary winding cam into operative relation with the builder arm in opposition to 30 said yielding means, and a locking member carried by the builder arm to hold the primary winding cam in operative relation with the builder arm.

7. In a builder motion, the combination 35 of a builder arm, primary and service winding cams for selectively operating the builder arm, yielding means tending to relatively move the cams axially in one direction and render the primary winding cam 40 inoperative, manually operated means for relatively moving the cams in the opposite direction, and a locking member mounted on the builder arm and engaging the side of the primary cam to prevent relative movement of the cams responsive to said yielding 55 means.

8. In a machine of the character described, the combination of a series of spindles and yarn guiding means, a builder 50 arm for relatively traversing the spindles and guiding means, a primary winding cam and a service winding cam mounted for rotative movement in unison, one of said cams having an opening, a locking member 55 mounted on the builder arms for holding the winding cams in predetermined relation to the builder arm, and means effective for relatively moving the cams in an axial direction when the said opening is presented 60 to the locking member.

9. In a machine of the character described, the combination of yarn winding and guiding means, a builder arm for relatively traversing the winding and guiding means, 65 a primary winding cam and a service wind-

ing cam, yielding means tending to move the primary winding cam axially relative to the service winding cam, manually-operated means for moving the primary winding cam axially in opposition to said yielding means, 70 a latch for holding said manually-operated means when released by the attendant, and a lock for holding the primary winding cam after the latch has been tripped.

10. In a machine of the character described, the combination of yarn winding and guiding means, a builder arm for relatively traversing the winding and guiding means, a primary winding cam and a service winding cam, yielding means tending to 80 move the primary winding cam axially relative to the service winding cam, manually-operated means for moving the primary winding cam axially in opposition to said yielding means, a latch for holding said 85 manually-operated means when released by the attendant, and a lock rendered effective by rotary movement of the primary cam to hold the said cam in operative relation with the builder arm until a predetermined number of preliminary windings have been laid upon the carrier. 90

11. A builder motion comprising a builder arm, a primary winding cam and a service winding cam, spring means between the 95 cams tending to move the primary winding cam into inoperative relation with the builder arm, hand-operated devices for moving the primary winding cam into operative relation with the builder arm, and a lock rendered effective by rotative movement of the primary winding cam after it has been moved by the hand-operated devices for locking the primary winding cam in operative relation to the builder arm. 100

12. In a machine of the character described, the combination of spindles and yarn guides, a builder motion comprising a builder arm, a primary winding cam and a service winding cam, springs for moving the primary winding cam away from the service winding cam, manually-operated means for moving the primary winding cam in opposition to the springs, a latch to temporarily hold the primary winding cam in position 115 against the action of the springs, a lock for the primary winding cam made effective by rotation of the cam, and means for tripping the latch after the lock has become operative.

13. In a builder motion, a builder arm, primary and service winding cams mounted for rotation in relative set positions, springs between the cams normally acting to move the primary winding cam into inoperative relation with the builder arm, a lever for 120 manually moving it into operative relation with the builder arm, a latch for temporarily holding the lever with the cam in operative position, means for tripping the latch, and a lock operating to hold the primary wind- 125

ing cam in operative position after the latch is tripped.

14. In a builder motion, the combination of a builder arm, primary and service winding cams, means constantly acting to separate the cams, a locking member mounted on the builder arm, and by engagement with the side of the primary winding cam adapted to prevent separation of the said cams responsive to the constantly acting means, manual depression of the builder arm permitting movement of the cams toward or from each other.
15. In a builder motion, the combination of a builder arm, primary and service winding cams movable toward and from each

other, yielding means constantly acting to separate the cams, a hand lever, dogs operated through the hand lever for moving the cams toward each other, a lock for locking the hand lever with the cams in close relation, pins carried by the service winding cam for tripping the lock to free the hand lever, a locking member mounted on the builder arm and acting on the side of the primary winding cam to hold the cams in close relation until a predetermined position of the cams is reached.

In testimony whereof, I have signed my name to this specification.

HARRY A. LEONARD.
